CLAIM

The ornamental design for an electronic calculator with a printer as shown and described.

DESCRIPTION

FIG. 1 is a right, top, front perspective view of an electronic calculator with a printer in accordance with our new design; FIG. 2 is a front elevation view thereof; FIG. 3 is a rear elevation view thereof; FIG. 4 is a top plan view thereof; FIG. 5 is a bottom plan view thereof; FIG. 6 is a right side elevation view thereof; FIG. 7 is a left side elevation view thereof; FIG. 8 is a sectional view taken along arrow 8-8 of FIG. 2, omitting internal mechanisms; FIG. 9 is a left, top, rear perspective view thereof; FIG. 10 is a right, top, front perspective view thereof and further showing digital display numerals; and, FIG. 11 is a right, top, front perspective view thereof and further showing a printer paper roll.

The broken lines shown in the figures depict portions of the electronic calculator with a printer that form no part of the claimed design.

1 Claim, 11 Drawing Sheets
